UNITED STATES PATENT OFFICE.

EDWARD LUCK, OF STAMFORD STREET, BLACKFRIARS, COUNTY OF SURREY,
ENGLAND.

APPARATUS FOR THE CONVERSION OF UNMALTHED GRAIN.

SPECIFICATION forming part of Letters Patent No. 278,985, dated June 5, 1883.

Application filed March 30, 1883. (No model.) Patented in England September 7, 1881, No. 3,881; in France February 3, 1882, No. 147,201; in Belgium February 13, 1882, No. 57,064; in Germany February 14, 1882, No. 19,535; in Spain June 7, 1882, No. 2,714, and in India July 13, 1882, No. 741.

To all whom it may concern:

Be it known that I, EDWARD LUCK, a citizen of England, residing at Stamford Street, Blackfriars, in the county of Surrey, England, have invented a new and useful Improvement 5 in Apparatus for the Conversion of Unmalted Grain, also applicable for heating or boiling other substances with steam, air, or gases, (for which I have obtained patents in Great Britain, dated September 7, 1881, No. 3,881; France, dated February 3, 1882, No. 147,201; Belgium, dated February 13, 1882, No. 57,064; Germany, dated February 14, 1882, No. 19,535; Spain, dated June 7, 1882, No. 2,714, and India, dated July 13, 1882, No. 741,) of which 10 the following is a specification.

My invention relates to improvements in apparatus used in the gelatinization of unmalted grain, or its conversion into a wort or material 15 suitable for brewers, distillers, and other purposes.

The construction and mode of operation of said apparatus will be readily understood on reference to the accompanying drawings, in 20 which—

Figure 1 shows a vertical section of the same; Fig. 2, a part plain; Fig. 3, a sectional plan on line X X, Fig. 1; and Figs. 4 to 9, details to an enlarged scale.

The apparatus consists of a closed vessel, A, 25 through the stuffing-box *a* in the cover of which passes a hollow shaft, B, to the upper end of which steam is supplied by a pipe, *b*. To the shaft rotary motion is imparted by 30 means of bevel-wheels *b' b''*, of which *b'* is driven by any convenient motor. The lower end of the shaft B is carried in a stop-bearing, *a'*, and near its lower end it has formed upon it the radially-projecting arms C, the peculiar 35 form of which will be more readily seen in the enlarged part elevations of the shaft at right angles to each other at Figs. 4 and 5, and the part plan at Fig. 6. Each arm consists of an inclined plate, *c*, on which are flanges *c' c''*, forming an inclined trough that communicates 40 with the interior of the shaft B by means of the openings *b''*, as shown at Fig. 5, in which

the section through the arm is taken on the line Y Y, Fig. 4. To these arms C are attached extensions C', formed as shown in the detached 50 front view at Fig. 7, and end view at Fig. 8—namely, having a plate, *c''*, which is bolted to the face of the plate *c*, and flanges *c' c''*, that butt up against those *c'*, so as to form an extension of the trough, which is closed by the 55 perforated cover D, (shown separate at Fig. 9,) extending over both parts, and secured by screws, as shown. The trough is also closed at the outer end by a piece, *c'*.

The outer ends of the extensions C' are stayed 60 from the shaft B by means of rods E, the upper ends of which are secured to a ring, F, bolted between the flanges of the shaft B, which, for convenience' sake, is made of two 65 separate lengths. The arms are also connected together at their outer ends by the rods G.

From the above-described arrangement it will be seen that as the shaft B, with the hollow arms C C', is made to revolve in the direction of the arrows, steam will issue from the perforations in a backward and downward direction among the liquor and grain to be gelatinized contained in the vat, and in heating or 70 boiling the contents, so as to effect the gelatinization or conversion of the grain, the steam 75 will, in impinging against the bottom of the vat, prevent any accumulation of the grain at that point, while at the same time the inclined front faces of the arms will, in revolving with the shaft, tend to propel the grain and liquid 80 in an upward direction, thus insuring an effectual stirring up of the mass.

The vat is provided with a gage-glass at H for observing the height of the liquid, and with a man-hole closed by a cover, I, through which 85 the grain to be gelatinized or converted, the liquid acid, and any other ingredients necessary for the process are introduced. A safety-valve and pressure-gage are also provided, and a valve, K, at bottom for emptying the liquor 90 out of the vat; also a cock at any convenient point for drawing off a sample of the liquors for testing.

The vat may be of any suitable material; but

when acids are used in the process I prefer to make the internal parts of gun-metal or other material capable of resisting their action.

The part of the plates $c c'$ outside the troughs $c' c''$ may be formed with perforations, if desired, to lessen the resistance of rotation of the arms through the mass.

Although I have described the said apparatus as applied to the gelatinization or conversion of unmalted grain, yet it will be evident that it may be used with equal advantage for treating or boiling other liquid or semi-liquid or granular substances or washes with steam, air, or gases, such as for soap-boiling or for the candle-making processes.

I am aware that stirrers have been used in connection with steam to comminute or disintegrate grain for distill-mash or for other purposes.

I am also aware that steam has been introduced into a receiver through pipes radiating from a central pipe, which are rotated by the egress of the steam to permeate the mash, and at the same time stir and agitate the same by the said rotating pipes.

Having thus described the nature of my invention and the best means I know of carrying the same into practical effect, I claim—

1. In apparatus for the gelatinization or conversion of grain, or for treating other substances with steam, air, or gases, the combination, with a closed vessel, of a revolving hollow vertical shaft with hollow arms having inclined perforated faces, so that the steam passing down the shaft and into the arms will issue through the perforations in a backward and downward direction, substantially as and for the purposes set forth. 30

2. The combination of the shaft B, arms C', and perforated covers D, arranged and operating as herein described. 35

In testimony whereof I have signed my name to this specification, in the presence of two subscribing witnesses, this 14th day of March, A. D. 1883.

EDWARD LUCK.
